UNITED STATES PATENT OFFICE

MENDEL NEVIN, OF BROOKLYN, NEW YORK

HYPODERMIC SYRINGE AND THE LIKE

Application filed April 9, 1929. Serial No. 353,716.

This invention relates to hypodermic syringes and the like.

The liquid introduced hypodermically by a syringe should be prepared and maintained in aseptic condition. That is, it should be free from bacteria and similar bodies and it should not contain toxic substances which if present in sufficient amount, might be harmful when introduced hypodermically into a patient. It has been found difficult in using the type of hypodermic syringe heretofore employed to always maintain the liquid in an aseptic condition. This is due to an effect which occurs in the use of the syringe. For example when a syringe is employed in an infected area, the tip of the needle may rest in a position surrounded by toxic substances or germs. As long as the aseptic fluid is forced into the area through the needle, there is no chance for these toxic substances and germs to enter the lumen and mount into the interior of the syringe, but the instant the pressure of the plunger on the liquid ceases, due to release of the pressure of the hand, the plunger tends to move back in a direction away from the needle and a back flow occurs sucking the objectionable toxic matter back into the ampule, cartridge or other container of the liquid. As soon as this occurs the liquid therein becomes contaminated with these objectionable bodies and loses its aseptic nature. When the syringe is then withdrawn from the infected area and plunged into a healthy area, the fluid which is now contaminated flows into this area and tends to set up an infection or to give it a toxic condition.

The principal object of the present invention accordingly is to provide a simple and efficient means to avoid contamination of the syringe liquid as indicated. Another object of the invention is to provide an inexpensive device of this kind which may be easily kept clean. Another object of the invention, when I employ a removable ampule as described in the preferred embodiment of the invention below, is to provide a simple and efficient means to avoid accidental disengagement of the ampule from its holding means.

Further and more specific objects, features

and advantages will appear from a consideration of the drawings and the detail description hereinafter set forth, when taken in conjunction with the claims.

Preferred forms of the invention are shown in the drawings, in which

Fig. 1 is a longitudinal sectional view of a hypodermic syringe showing the invention embodied therein;

Fig. 2 is an enlarged detail view of the parts, arranged in the order of their assembly for allowing the plunger to move in one direction but preventing its motion in the opposite direction;

Fig. 3 is an enlarged detail plan view of the gasket shown in Fig. 1 pierced with pin holes and acting as a valve to obstruct back flow of liquid;

Fig. 4 is an enlarged detail plan view of a modification of the gasket shown in Fig. 3; and

Fig. 5 is an enlarged detail side view partly in section of another modification of the gasket shown in Fig. 3.

Referring to Figs. 1 and 3, the syringe comprises an elongated cylindrical barrel or frame 1 exteriorly threaded at one end to receive a cap 2. The other end of the barrel is exteriorly threaded to receive a cap 3 having an exteriorly threaded plug 4 and a flange 5 abutting the end of the barrel 1. The outer end of cap 3 is provided with an exteriorly threaded extension 6 having a small bore 7 extending through to a curved recess or seat 8 on the inner face of the plug 4. This seat 8 is preferably provided with a resilient packing or soft rubber gasket 9 with which the end of a glass ampule 10 is adapted to make fluid-tight connection after the end of the ampule has been broken to release the aseptic fluid therein.

The gasket 9 as shown in Figs. 1 and 3, is funnel-shaped terminating at its smaller end in a floor 11 which is pierced with holes 12. These holes pass completely through the floor. They are here shown slightly exaggerated in diameter. They are made by piercing the rubber with a piercing tool whose diameter is not greater than that of an ordinary straight pin. After this tool has passed

through, the holes are scarcely visible because the rubber collapses so that the holes are substantially closed up. Upon distending the rubber as by stretching it, the holes 5 become visible and in distended condition they are able to freely allow the passage of liquid therethrough. These holes expand when pressure is applied to the liquid and contract when it is released. As long as 10 pressure is on the liquid it flows from the ampule 10 through the gasket and out through the needle. When pressure is released the holes close against the inflow of fluid from an infected area into the aseptic 15 liquid when the pressure is released, as will be described more fully below.

A needle supporting nut or thimble 13 is 20 interiorly threaded at one end to screw on to the extension 6 and has a bore 14 aligned with bore 7. A hollow hypodermic needle 15 is disposed and held in bores 7 and 14.

The barrel 1 is cut away to some extent at 25 16 and to a larger extent on the opposite side at 17. Through this larger opening 17 there is inserted the ampule 10 preferably of glass having a tapered end 18, which before introduction is preferably broken. A plug or piston 19 of soft rubber is in the other end of the ampule. The ampule 10 contains aseptic 30 medicament 20 which is prepared and placed in the ampule and sealed therein under stringently antiseptic conditions. When the ampule is to be placed in the barrel, the sealed end 18, as mentioned above, is broken off and the lower end of the ampule is seated upon the funnel shaped gasket 9. The chamber in barrel 1 to receive the ampule 10 is necessarily of ample dimensions to permit the insertion of the ampule. When the ampule 40 is inserted in place, simple means are provided to engage and hold fast the lower end 18 on its cushioned seat to make a tight joint at that point.

This ampule clamping means comprises a 45 longitudinal movable member such as sleeve 21, disposed in the upper end of the barrel and having a stem 22 provided with exterior threads 23 with preferably large pitch to engage similar threads on a bore 24 in cap 2. The outer end of stem 22 is provided with a 50 knurled stud- and socket-head member 25 which permits the plunger of the syringe to move towards the needle as long as pressure is applied thereon, but which prevents the 55 movement away from the needle of the plunger thus preventing the back flow of matter from the tissue after which the injection is made, into the interior of the ampule. This head 25 in addition to performing the action 60 mentioned, also serves to permit manual exterior operation of the plug 21 to advance or retract it by rotation with respect to the end of the ampule 10.

At the lower end of the plug 22 is a recess 65 26 to accommodate the head 27 which is

screw-threaded on to the end of a piston rod or plunger 28 which slidably extends through the bore 29 in plug 22 and has an operating handle 30 on its outer end.

Adjacent the end 31 of the plug 22 which abuts the end of ampule 10 the plug is provided with a depending peripheral rim or flange 32, extending down the side wall of the ampule, the inner face of which is downwardly and outwardly bevelled or flared and serves to abut the upper end of the ampule 10 to better hold it in place. Between the upper end of the barrel 1 and the stem 22 an annular space is provided in which is seated a coiled spring 33, the lower portion of which rests on the shoulder 34 formed at the point where the stem meets the lower portion of the plug 21. The upper portion of the spring lies against the under surface of the cap 2. The spring is of sufficient diameter to allow 85 the stem and screw-threads thereon to pass freely back and forth through it. This spring is provided in order to insure that the removable cap 2 shall be firmly maintained in place on the end of the barrel 1. It is plain that in rotating the member 25 to move the plug 21 into and out of engagement with the ampule 10, there is a tendency at the same time to turn the cap 2 to disengage it from the end of the barrel. Since the threads 23 pass through engaged threads on this cap, there is a tendency to unscrew the cap upon movement of the plug 21. Pressure of the spring 33 against the under side of the cap tends, however, to hold it firmly in position 90 against motion that may be imparted to it by the movement of the plug. By thus maintaining it in position, the proper position of the plug is assured so that it will engage and disengage the ampule as desired. It is plain that if the cap 2 becomes unscrewed a sufficient distance, it will cause the plug to travel upwardly a sufficient distance so that it cannot engage the ampule upon movement 95 of the head 25. By restraining movement of the cap the spring thus tends to insure the proper engagement of the ampule and to insure accordingly correct functioning of the device.

The removable cap with the spring member holding it in place to avoid accidental disengagement of the ampule-holding member from the ampule, may be employed with or without the device described below for permitting the plunger to move toward the needle but preventing movement in the 100 opposite direction.

The bevelled stud- and socket-head member 25 comprises a socket head 35 and a stud-head 36, as shown more clearly in Fig. 2. The socket-head 35 comprises a substantially cylindrical bevelled portion 37 tapering to a boss 38 provided with three slots 39. An opening 40 in the center of the head is for the piston shaft 28. The stud-head 36 is mounted to move towards and away from the nee- 105 110 115 120 125 130

dle and is substantially cylindrical at the bottom and provided with a sloping surface so that when it is assembled with the head 35, the thumb and fore finger can rest on the 5 sloping surfaces of these heads for a purpose to be described later. It comprises a stud 41 which is centrally bored and is supported by three equi-distantly spaced fins 42 projecting from the rimmed aperture 43 of the head. The space between the stud and the wall of the aperture is formed to admit the boss 38 so that the slots 39 have their edges resting respectively against the sides of the fins 42. The stud is provided with 10 three ball-bearings 44 seated at equi-distant intervals therein and arranged to move freely back and forth through the wall of the stud near the upper portion thereof. Adapted to press against the under side of the stud- 15 head 36 is a coiled spring 45. Fins 46 on the stem 22 are arranged to lie in the extremities of slots 39 after the head 36 has been placed in position and the fins 42 moved upwardly as far as they will go into the slots. 20

In assembling this stud- and socket-head member, the head 35 is placed in position with respect to head 36 with the slots and fins disposed as just indicated. The spring 25 45 is then placed beneath the stud 41 with its upper edge contacting with one or more of the fins 42. The sleeve 21 is then placed in position with its fins 46 engaging respectively the lower portions of the slots 39. A ring 47 of approximately the diameter of a 30 circle passing through the outer edges of the fins 46, having been placed in position about these fins, is advanced at the same time that the fins are inserted in the slots 39 so that it seats in a recess at 48 formed at the lower 35 portion of the boss 38 to hold the parts in assembled position. The interior of the lower wall of the boss 38 is bevelled corresponding to a bevel between the fins 46 so that these members will grip one another. 40

When assembled, the aperture 40 in head 35, the central bore of the stud 41 and the aperture 29 of the sleeve 21 are all aligned so that the plunger shaft may pass therethrough, after which the head 27 of the 45 plunger may be screwed on.

The interior of the head 36 has a conical bearing surface 49 so that when the stud-head moves away from the needle in the assembled position shown in Fig. 1, the ball-bearings 50 will wedge against the conical bearing surface on one side of the plunger shaft and prevent movement of the shaft away from the needle. However, when the stud-head is moved toward the needle which will be the 55 case when pressure is exerted by the hand to force the plunger forward to eject the liquid, the ball-bearings will be away from the wedging position and will allow the shaft to move towards the needle and as long as the stud-head 36 remains in this position the plunger

28 may in fact move in either direction freely. Normally the spring 45 keeps the head 36 pushed upwardly as shown in Fig. 1 so that the plunger 28 will move freely only towards the needle. 70

If it is desired to withdraw the shaft and piston head after the shaft has been moved forward to eject the contents of the ampule, this can be done by placing the thumb and fore-finger on the sloping sides of the head 75 36 and pressing it towards the needle, thus moving the stud so that the ball-bearings are not in engagement with the conical surface 48 of the socket member 35. When in this position as pointed out above, the shaft may be pulled up by the other hand out of the ampule. 80

In operation when an ampule is engaged in operative position the handle 30 can be pushed in, forcing the head 27 on plunger 28 forward against the piston plug 19 to move it forward in the ampule 10 and expel the medicament 20 through the holes 12 in the gasket 9 through the bore 7 and the needle 15. Flow of liquid through the gasket holes 85 is permitted because the pressure exerted by the plunger 28 is sufficient to distend these holes sufficiently to allow passage of the liquid. The expansion of the rubber under pressure and its subsequent contraction when the pressure is released cause these holes to 90 act as valves, that is, liquid can pass outwardly since the pressure of the plunger is outwardly but liquid is restrained from passing back through these holes because there is insufficient pressure exerted in this direction 95 in use. When the plunger has advanced a desired distance to expel a sufficient quantity of fluid pressure of the hand against the handle 30 may be released and instantly the shaft 100 is prevented from backward movement by the wedging of the ball-bearings against the plunger 28 and conical bearing surface 49. In this way the tendency of the piston and shaft to recede with consequent sucking in of 105 liquid containing toxic or other objectionable substances into the aseptic liquid of the ampule is checked. After the plunger 28 and piston 19 have been forced to their furthermost position in the ampule, if it is desired 110 to withdraw the shaft, the thumb and forefinger are placed on the sloping sides of the head 36 which is depressed, whereupon the shaft may be withdrawn by the handle 30. 115

In Fig. 4 a modification of the gasket 9 is shown. There the floor 11 of the gasket is slit to form flaps 50 and 51. For this purpose three slits are made—one diametrical slit extending part of the way across the floor and two oppositely disposed arcs each adjoining the diametrical slit and substantially bisected by it. In Fig. 5 is shown a still further modification in which the floor 11 is not pierced or slit but is solid throughout. A short distance above this floor on the side walls of the gasket, two short slits 52 are made. They 120 125 130

are substantially diametrically opposite one another as here shown.

The gasket shown in Fig. 4 acts similarly to that shown in Fig. 3. Liquid flowing from ampule 10 under pressure of the plunger forces the flaps 50 and 51 to open outwardly to allow liquid to flow through the bore 7 and needle 15 and when the pressure ceases these flaps close against flow of the liquid back into the ampule 10. Similarly the gasket shown in Fig. 5 allows liquid to flow from the ampule 10 through the slits 52 under pressure of the plunger and when the pressure is released the slits close again against entrance of liquid through the passages mentioned.

While I have described my improvements in detail and with respect to preferred forms thereof, I do not desire to be limited to such details or forms since many changes and modifications may be made and the improvements embodied in widely different forms without departing from the spirit and scope of the invention in its broader aspects. Hence I desire to cover all modifications and forms coming within the language or scope of any one or more of the appended claims. What I claim is:—

1. In combination a hypodermic syringe having a needle, a removable medicament container, a plunger on a shaft for driving liquid from the container, a movable container-clamping member and a wedging device engaging said shaft mounted on said member for permitting the plunger to move towards the needle but wedging and preventing movement in the opposite direction.

2. In combination a hypodermic syringe having a needle, a removable medicament container, a plunger on a shaft for driving liquid from the container, a movable container-clamping member and a device engaging said shaft mounted on said member, including a wedge, a spring for holding said wedge in position to engage the shaft, for permitting the plunger to move towards the needle but wedging and preventing movement of the plunger in the opposite direction to prevent suction through the needle.

3. In combination, a hypodermic syringe having a needle, a removable ampule of glass or like material sealed at one end by said glass or the like, said end being broken off when the ampule is used, a plunger on a shaft for driving liquid from the ampule, a movable ampule-clamping member and a spring-held device engaging said shaft mounted on said member for permitting the plunger to move towards the needle but preventing movement in the opposite direction, said device including a stud and socket, said socket having a wedge-shaped bearing surface, said stud having a part bearing thereagainst and said spring tending to keep said part forced against said bearing surface.

4. In combination, a syringe having a

frame, a removable liquid medicament tube of glass or like material sealed at one end by said glass or material, said end to be broken off when the ampule is used, a needle to receive liquid from the chamber, a plunger for driving liquid from the chamber and a device for permitting the plunger to move toward the needle but preventing movement in the opposite direction, and a member operable at will to prevent the operation of said device so that said plunger may be moved away from said needle, and a gasket extending around the forward end of the ampule, and forcing a tight joint with said frame between it and said needle, said gasket having an opening so formed that under normal pressure flow of liquid is obstructed but under increased pressure the opening expands to allow liquid to pass therethrough.

5. In combination a syringe having a frame, a removable liquid medicament tube of glass or like material sealed at one end by said glass or material, said end to be broken off when the ampule is used, a needle to receive liquid from the ampule, a plunger driving liquid from the chamber, a device for permitting the plunger to move towards the needle but preventing movement in the opposite direction, a stud- and socket-member, part of said member being attached to said frame, said plunger passing through said stud- and socket-member, said socket member having a wedge-shaped bearing surface, said stud-member having a part bearing thereagainst, and a resilient member tending to keep said part forced against said wedge-shaped socket bearing, whereby movement of said plunger away from said needle is prevented by contact of said bearing member with said plunger and said wedge-shaped bearing, and a funnel-shaped gasket forming a tight joint between said frame and said ampule between the end thereof and said needle, said gasket having its base pierced by holes restraining the passage of liquid into the ampule but allowing liquid to pass from the ampule upon pressure being exerted thereon by said plunger.

6. In combination, a syringe having a removable ampule, a needle to receive liquid from said ampule, a plunger for driving liquid from the ampule, a movable ampule-engaging member, and a device for permitting the plunger to move towards the needle but preventing movement in the opposite direction, comprising stud- and socket-heads, one of said heads being attached to said ampule-engaging member, said stud- and socket-heads being bored to receive said plunger, said stud head having stud-supported ball-bearings, said socket head having an interior conical bearing surface against which said ball-bearings rest on one side and on the other side contact with said plunger, and a spring tending to keep said bearings in position.

- tion against said conical bearing surface whereby motion of said plunger towards said needle will tend to move said bearings away from said bearing surface and thus allow 5 the plunger to move easily in that direction but upon tendency of the plunger to move in the opposite direction, said bearings will wedge against said bearing surface and said plunger to prevent such movement.
10. 7. In combination, a syringe having a removable ampule, a needle to receive liquid from said ampule, a plunger for driving liquid from the ampule, a movable ampule-engaging member, and a device for permitting 15 the plunger to move towards the needle but preventing movement in the opposite direction, comprising stud- and socket-heads, said socket head being attached to said ampule-engaging member and said stud-head being mounted to move toward and away 20 from said needle, said heads and member being aligned together and having openings for receiving said plunger shaft, said socket-head having an interior conical bearing surface around said shaft, said stud having ball- 25 bearings bearing on said shaft on one side and said bearing surface on the other side so that when said stud head moves away from said needle, the ball-bearings will wedge 30 against said bearing surface and shaft and prevent movement of the shaft away from the needle, said stud-head upon manual movement towards said needle allowing said shaft to move away from the needle, and a spring 35 tending to keep the stud-head forced away from the needle to normally prevent movement of the shaft in a direction away from the needle.
8. In combination, a syringe having a barrel and a removable ampule therein, a removable cap at one end of said barrel, a movable member passing therethrough and abutting against one end of the ampule when in 40 position, means exteriorly of the barrel and connected to said member and manually operable to move it to its operative and inoperative positions and a resilient member cooperating with said cap to restrain it from movement upon movement of said means, whereby 45 by accidental disengagement of the member from the ampule is restrained.
9. In combination, a syringe having a barrel and a removable ampule therein, a removable cap on one end of said barrel with a threaded bore therein, a longitudinally movable sleeve within the end of the barrel adjacent the ampule to bear thereagainst when 50 in position, a threaded extension on said sleeve passing through the bore and said cap to be manually operated exteriorly of the barrel to move the sleeve to its operative and inoperative positions, and a resilient member 55 cooperating with said cap to maintain said cap in position, whereby accidental dis- 60
- engagement of the member from the ampule is restrained.
10. In combination, a syringe having a barrel and a removable ampule therein, said ampule having a piston plug in one end, a removable cap over one end of the barrel, a movable member passing therethrough and adapted to abut against the end of the ampule, a resilient packing in the barrel for the other end of the ampule and with which the other end of the ampule is adapted to make fluid tight connection, manually operable means on the outside of the barrel for moving said member to abut against the end of the ampule and cause the opposite end of the ampule to press against said packing and a spring cooperating with said cap to keep it in position, whereby accidental disengagement of the member from the ampule is restrained.
- In testimony whereof I have signed my name to this specification.
- MENDEL NEVIN.
